UNITED STATES PATENT OFFICE

168,900

MULTIPLE WRENCH

Simon Lutsker, Cleveland Heights, Ohio

Application January 26, 1952, Serial No. 18,246

Term of patent 14 years

(CL. D54—13)

To all whom it may concern:

Be it known that I, Simon Lutsker, a citizen of the United States, residing at 3647 Harvey Road, at Cleveland Heights, county of Cuyahoga, and State of Ohio, have invented a new, original, and ornamental Design for a Multiple Wrench, of which the following is a specification, reference being had to the accompanying drawing, forming a part hereof.

Fig. 1 is a side elevational view of a multiple wrench, showing my new design;

Fig. 2 is an elevational view of the side opposite Fig. 1;

Fig. 3 is a top plan view;

Fig. 4 is a bottom plan view;

Fig. 5 is an elevational view of the left end of Fig. 3; and

Fig. 6 is an elevational view of the right end of Fig. 3.

I claim:

The ornamental design for a multiple wrench, as shown.

SIMON LUTSKER.
